HIGH-PRESSURE PISTON OR RECIPROCATING COMPRESSOR OR THE LIKE

Application filed January 26, 1928, Serial No. 249,627, and in Switzerland April 19, 1927.

This invention relates to high pressure piston or reciprocating compressors or the like of the kind in which the driving apparatus drives the compressor through the medium 5 of an oscillating column of liquid.

According to the present invention the intermediate piston of the compressor is located above the working piston of the compressor. The liquid column directly actuated by the 10 piston of the driving apparatus can either act on that face of each intermediate piston which is nearer to or directed towards its respective working piston or alternatively, on that face of each intermediate piston which is 15 remote from its respective working piston.

The invention is diagrammatically illustrated by way of example in the accompanying drawing, in which—

Figure 1 is a section through the two upper stages of a compressor,

Figure 2 is a view partly in plan and partly in cross-section on the line I—I of Figure 1, and

Figure 3 shows a modification according to 25 the invention.

In the construction shown in Figures 1 and 2 the cylinders 3 and 4 for the intermediate pistons 5 and 6 of the compressor are mounted in the casings 1 and 2.

30 The primary piston 8 actuated by a driving machine not shown, reciprocates in the cylinder 7 containing a column of liquid. The compressor pistons 10 and 11 draw the working medium into the cylinders 12 and 14

35 where it is compressed, the intermediate piston 5 of one stage being located above the compressor piston 10 and the intermediate piston 6 of the other stage above the compressor piston 11. The liquid column in the cylinder 7

40 actuated by the primary piston 8 of the driving machine is disposed between those sides of the intermediate pistons which face towards the piston of the compressor and at a point lower than the liquid column 13 between the two intermediate pistons 5 and 6.

45 Figure 3 shows a modification in which the liquid column in the cylinder 7 actuated by the piston 8 of the driving machine, not shown in the drawing, is located on that side 50 of the pistons 5, 6 remote from the piston of

the compressor and at a point higher than the liquid column 13 between the pistons 5 and 6.

When the piston 8 (Figure 2) moves in the direction of the arrow 15 liquid passes through the passage 16 to the underside of the piston 6 which is thus forced upwardly and draws the medium to be compressed, for example gas, into the cylinder 14. At the same time, however, the liquid column 13 forces the piston 5 downwardly whilst the liquid column between the underside of the piston 5 and the piston 8 is forced through the passage 17. The compressor piston 10 is thus caused to compress the medium drawn into the cylinder 12.

By means of the arrangement shown the pistons 10 and 11 which effect the compression may be arranged as downwardly acting pistons, when the following advantages are obtained.

(1) The impurities drawn in by the gas to be compressed are held back from the stuffing box as they cannot pass between the piston and the packing, but fall from the end face of the piston to the valve end of the cylinder.

(2) Any liquid drawn in falls to the valve end of the cylinder, and, if much liquid is present, it is forced out through the delivery valves so that no water hammer can take place. Liquid always clings—even if only in small amounts—to the valves, so that the liquid remaining between the valve and its seating protects the valves when they come down on to their seatings.

(3) The cylinders, instead of being arranged vertically, may be suspended downwards, which is particularly of advantage for those stages operating at very high pressures. This arrangement is very important since,

when super-high pressure compressors are arranged vertically, safety devices must be provided, as conditions—due to unforeseen faults in the material, or to structural modifications owing to varying strains, or due to chemical action by the medium to be compressed—are present which may lead to trouble in the compressor, although such conditions may be disregarded in compressors working at normal pressures. The suspended arrangement of the cylinders also

enables the safety devices to be arranged in the foundation 18, i. e., the foundations may be constructed so that the engine room space need not be used to house these safety devices.

5 I claim:

1. In a high pressure reciprocating compressor, the combination with a horizontally arranged primary piston effecting a positive movement, of a plurality of vertically arranged intermediate pistons, a plurality of compressor pistons arranged beneath said intermediate pistons, and adapted to be actuated thereby, an oscillating column of liquid 10 between one side of said primary piston and one of said intermediate pistons, an oscillating liquid column between the other side of said primary piston and another of said intermediate pistons, and an oscillating 15 column of liquid between said intermediate pistons.
2. In a high pressure reciprocating compressor, the combination with a horizontally arranged primary piston effecting a positive 20 movement, of a plurality of vertically arranged intermediate pistons, a plurality of compressor pistons arranged beneath said intermediate pistons and adapted to be actuated thereby, an oscillating column of liquid 25 between one side of said primary piston and one of said intermediate pistons, an oscillating liquid column between the other side of said primary piston and another of said intermediate pistons, said columns acting on 30 that face of each intermediate piston, which is nearest its respective compressor piston, and an oscillating column of liquid between 35 said intermediate pistons.
3. In a high pressure reciprocating compressor, the combination with a horizontally arranged primary piston effecting a positive 40 movement, of a plurality of vertically arranged intermediate pistons, a plurality of compressor pistons arranged beneath said intermediate pistons and adapted to be actuated thereby, an oscillating column of liquid 45 between one side of said primary piston and one of said intermediate pistons, an oscillating liquid column between the other side of 50 said primary piston and another of said intermediate pistons, said columns acting on that face of each intermediate piston which is remote from its respective compressor piston, and an oscillating column of liquid 55 between said intermediate pistons.

In testimony whereof I have affixed my signature.

CHARLES SCHAER.
